BABY MOISTUREPROOF DIAPER
PROTECTOR

Tessie Malamut, Brooklyn, N. Y.

Application August 14, 1948, Serial No. 44,260

1 Claim. (Cl. 128—287)

1

This invention relates to new and useful improvements in diaper protectors, and, more particularly, the aim is to provide a novel and valuable baby pants of improved behavior when worn by an infant over a diaper.

The new diaper protector prevents moisture from reaching the infant's dress, and to that end a waterproof ply of material is included. The arrangement is such that with said ply innermost nevertheless chafing of the legs and abdomen is prevented, which chafing is a bothersome and sometimes serious problem when ordinary rubber baby pants are worn.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view showing an embodiment of the invention as now favored, raised at its opposite ends in the manner in which these portions of the garment would be arranged in the course of placing the same on an infant.

Fig. 2 is a plan view showing the garment spread flat, and looking at the inner side thereof.

Fig. 3 is an enlarged detail view, being a section taken on the line 3—3 of Fig. 2.

Fig. 4 is a similar view, being a section taken on the line 4—4 of Fig. 2.

Fig. 5 shows a piece of textile material as cut for edge facing the same to provide the outer ply of the garment.

Fig. 6 is a view for assisting to show the relationship, in the finished garment, between the aforesaid waterproof ply and said piece of textile material; said waterproof ply being shown in full lines.

Referring to the drawings more in detail, the garment shown is substantially of dumbbell outline, having like end sections 10 and 11 each shaped as a truncated triangle. Such triangles have their bases facing each other; and they are joined by a central section 12 of greater length than width and having its opposite sides symmetrically substantially arcuately concavely curved as shown best in Fig. 2.

The garment incorporates an outer ply provided by a single piece of cloth 14, cut to the outline shown in Fig. 5. To provide along the two concavely curved sides of the garment section 12 narrow inner facings 15, each established by stitching a seam as shown at 15' in Fig. 4,

2

extensions 16 are present, each for an infold along a line 17. To provide fairly wide inner facings for the garment sections 10 and 11 along the free end and along both of the sides of each of said sections, at each of said sections extensions 18, 18', 18" are provided, these to be infolded along the lines 19, 19', 19".

The extensions 16, having been folded and stitched to provide the facings 15', next at each 10 of the end sections 10 and 11 the sections 18 are folded and stitched to provide the inner facings 20, incidental to the establishment of a suitable seam, as one like the one next-mentioned. Then, at each of said sections 10 and 11, the 15 extensions 18' are folded and stitched to provide, incidental to the establishment of a seam such as that indicated at 21 in Fig. 3, the inner facings 22.

In connection with the cloth piece 14 which 20 as above is folded and stitched to provide the facings 15, 20 and 22, it will be noted from Fig. 5 that at the meeting portions of an extension 16 with an extension 18 a three-ply structure is provided; and the same is true in regard to the 25 meeting portions of an extension 18' with an extension 18". Thereby, a cushioning means is incorporated at all places where the garment may in any way constrictively engage the body of the infant.

30 The garment is completed by the addition of the piece of sheet material to provide the aforesaid waterproof ply, the addition of suitable detachable fastening means along the facings 20, and the stitching in place of a tab to be explained in a moment.

35 Said waterproof ply is constituted by a sheet 23 of a filmlike, waterproof and preferably transparent plastic of any of the kinds commonly purchaseable on the open market, which plastic sheet may be readily identified by its extreme thinness, a somewhat milky white appearance when backed by an opaque material, and such a fine feel to the fingers as to be almost doeskin like. This material has some slight degree of elastic 40 stretchability, but the elastic behavior is rather 45 sluggish.

A feature of the invention is the way in which 50 this sheet is shaped relative to the shape of the cloth piece 14 and the arrangement of the sheet 23 to said piece 14 and the manner of attachment thereto of said sheet 23. The outline of the sheet 23 (after it has been twice reversely folded to provide oppositely facing pleats 24, Figs. 2 and 3), relative to the outline of the cloth piece 55 14 (after the latter has been provided with its

facings 15, 20 and 22), is shown in Fig. 6, where-
in said piece 14 and its said facings are indicated
in dot and dash lines; it being explained that
the stitchings employed to establish said facings
further serve not only to lock, in folded condition,
the opposite ends of both pleats 24 and anchor
the end sections of the sheet 23 to the sections
10 and 11 of the garment, but also, at the same
time, the sheet 23 is so present that all along
the central section 12 of the garment the central
section of said sheet 23 is full-floatingly associated
with said section 12.

The aforesaid suitable detachable fastening
means along the facings 20 may be tie strings,
buttons and buttonholes, or any equivalent; and
the same are shown as constituting snap fasteners—for example, three sets of such fasteners at
each of the two garment portions to be overlapped
at each side of the infant's body. Of these fas-
teners, the male elements 26 thereof are herein
illustrated as placed along each of the facings 20
at the rear of the garment, that is, at its section
11 (the far section in Fig. 1), with the posts of
the said elements at the inner side of the gar-
ment; while the female elements 25 are herein
illustrated as placed along each of the facings
20 at the front of the garment, with the sockets
of said elements at the outside of the garment.
Thus, in placing the garment on the infant's body,
the side extremities of the section 11 will be ar-
ranged overlappingly of the side extremities of
the section 10.

The garment is completed when a tab 27, is
stitched in place. This tab or an equivalent may
or may not be used, but its presence is now con-
sidered a feature of considerable importance,
as by virtue of its inclusion a safety pin can be
used to attach the front of new garment to the
front of a diaper or to the front of a shirt on the
infant without injuriously affecting the function
of the waterproof sheet 23. The tab 27 is one
woven of a moisture absorbent yarn or thread,
and hence a piercing of the sheet 23 within the
confines of said tab would at worst result merely
in the creation of an orifice capable of no more
than a negligible action as a moisture passing one.

The behavior of the waterproof sheet 23, while
the garment is being worn, is to be emphasized.
Because of its free floating central portion said
sheet comfortably yet perfectly adapts itself to
the infant's body at and adjacent to the crotch.
The infant's frequently changing postures, and

5 the different conditions set up when the infant
is lifted, are all fully protectively compensated
for by the potential capacity of the sheet 23
for elongation to a much greater extent than per-
mitted by any natural elastic stretchability
thereof, due to the inclusion of the pleats 24. As
10 shown in Fig. 1, the central lengths of such pleats
may be caused temporarily entirely to disappear,
but at the same time side rufflings as indicated at
28 will be set up, causing the sheet 23 to hug the
thighs of the infant snugly and so fully protec-
tively.

15 While I have illustrated and described the
preferred embodiment of my invention, it is to
be understood that I do not limit myself to the
precise construction herein disclosed and the
right is reserved to all changes and modifications
coming within the scope of the invention as de-
fined in the appended claim.

20 Having thus described my invention, what I
claim as new, and desire to secure by United
States Letters Patent is:

25 A diaper protector having a crotch-engaging
central section and two end sections one for ex-
tending across the front of an infant's body and
the other for extending across the back of such
body, said structure including an outer ply of
30 water absorbent material and an inner ply of
waterproof material, said inner ply attached to
the outer ply only near the ends of the garment,
said outer ply having seamed inner facings at
35 said end sections, said waterproof ply being se-
cured to the outer ply by the same stitchings
which establish said facings, said waterproof ply
having transversely extending pleats, each pleat
40 secured only at its opposite ends and there se-
cured by said stitchings, and a tab of absorbent
material overlying the waterproof ply at one of
said sections, said tab stitched all around the
same to both plies.
